UNITED STATES PATENT OFFICE.

EARL H. SHERBONDY, OF CLEVELAND, OHIO.

SUPERCHARGING DEVICE FOR TURBO-COMPRESSORS.

1,346,564.

Specification of Letters Patent. Patented July 13, 1920.

Application filed April 8, 1918. Serial No. 227,333.

To all whom it may concern:

Be it known that I, EARL H. SHERBONDY, a citizen of the United States, residing at Cleveland, in the county of Cuyahoga and 5 State of Ohio, have invented certain new and useful Improvements in Supercharging Devices for Turbo-Compressors, of which the following is a specification.

This invention relates to means for controlling the action of a turbo-compressor that is adapted to be operated by the waste gases from an internal combustion engine to pump air to the carburetor of said engine. The device is more particularly adapted to 15 be applied to an airplane engine and, as set forth in detail in my co-pending case Serial No. 224,894, filed March 26, 1918, is designed to provide a constant supply of air to the carburetor of the engine, regardless of the 20 height at which the airplane may be.

This invention is intended to be used in conjunction with the controlling system shown in my said above mentioned co-pending case and is more particularly designed 25 to supply additional air to the carburetor at any desired time, so that the engine will be supercharged and an excessive amount of power will be available.

Another object of the invention is to provide a device which will automatically cause 30 the engine to be supercharged at sea level and as the airplane reaches higher altitudes, to return to its normal power output.

Other objects and advantages will appear 35 as the description proceeds.

Referring to the drawings, Figure 1 is a diagrammatic view of the controlling system and Fig. 2 is a view in section of the 40 device for causing the automatic super-

charging.

The turbo-compressor comprises the turbine wheel 1 and blower wheel 2, preferably rotating on the same shaft 3. The 45 turbine is intended to be operated by the exhaust gases from an internal combustion engine, which are led thereto through the exhaust pipe 4 and inlet casing 5, the gases finally escaping to the atmosphere through the pipe 6.

50 The centrifugal blower wheel 2 of any desired type, takes in air through the flaring mouth 7 and drives it into the collector ring 8 from whence it is led through a pipe (not shown) to the carburetor of the engine (not shown). A by-pass valve 5' is provided, which when open, by-passes the gases from

the inlet chamber 5 to the exhaust pipe 6, without passing through the buckets of the turbine 1.

The valve stem 9' carries at its other end 60 a piston 9 working in a cylinder 10. One side of the piston 9 abuts against the spring 11 and the other side is connected to an oil pressure line 12, the pressure of which may be maintained in any desired manner. 65

It is evident that upon varying the oil pressure in the line 12, the piston 9 will be actuated to move the valve 5' to by-pass more or less of the exhaust gases, whereby the speed of the turbine and, consequently, 70 the delivery pressure of the compressor may be controlled. It is evident that a high pressure in the oil line corresponds to a low compressor speed and low delivery pressure from the compressor. 75

The pressure in the oil line 12 is controlled by a valve V, interpolated in said line, the valve V being mounted in the casing 13. Oil passages 15 and 16 provide inlet and outlet means for the oil to and from 80 the valve V, the oil finally passing into the waste line 17. The valve V is controlled by a diaphragm D connected thereto by the rod 18. Confined above the diaphragm D, in a suitable casing 19, is a body of air under substantially atmospheric pressure. The lower side of said diaphragm D, is responsive to the delivery pressure from the air compressor, said pressure being led to the lower side of said diaphragm through the 85 pipes 20 and 21. The valve V and the valve 5' are shown in the position they would occupy when the airplane is at sea level, that is to say, the valve V closes the oil line 12, so that a high pressure is maintained therein, thereby opening the valve 5' and bypassing the gases and keeping the speed of the 90 turbo-compressor low.

As the airplane rises, the pressure within the pipe 20, which, through the mouth 7, is 100 in connection with the atmosphere, tends to fall, the pressure below the diaphragm tends to fall and the valve V is opened, due to the expansion of the confined air in the casing 19. This bleeds the oil line 12, the 105 spring 11 closes the valve 8, causing the turbine to run faster and the delivery pressure of the air compressor to remain substantially constant. The details of the valve V and diaphragm D, are shown and described 110 in considerable detail in said above-mentioned co-pending case.

In short, then, it is evident that a lowering of the pressure below the diaphragm D will cause an increase in the delivery pressure of the air compressor.

5 Means which constitute an important feature of this invention to automatically cause a lowering of this pressure below the diaphragm D, in the space which I will call S, will now be described.

10 A pipe 21 leading from the delivery pipe of the air compressor, leads into a Venturi tube 22, which in turn is provided with a mouth 23 leading to the atmosphere. Around the throat of the venturi, there is a

15 hollow annular collar 24, which is in connection with the interior of the venturi through a series of holes 25. The hollow collar 24, communicates directly with the space S through the pipe 20. The mouth of

20 the venturi is controlled by a valve 26, which valve is intended to automatically close the venturi as the airplane rises. It is accordingly made responsive to the atmospheric pressure in such a way that a de-

25 crease in the atmospheric pressure will cause the closing of the venturi. This may be accomplished in a number of ways, one of which I will now describe.

The valve 26 carries a valve stem 27, 30 which is vertically disposed and carries at its lower end a float 28, which floats in a suitable fluid 29, confined in a casing 30. The casing 30 is open to the atmosphere through an opening 31. Leading from the

35 casing 30 is a pipe 32, opening to a casing 33 of a suitable height. The lower part of the casing 33 is filled with the fluid 29. Confined above the level of the fluid 29, there is a body of air at substantially atmos-

40 pheric pressure. This air may be confined by means which is preferably manually adjustable, such as by a screw-threaded piston 34 and a bellows 35. The operation of the device will now be described.

45 Keeping in mind the fact that a lowering of the air pressure within the space S will cause the air compressor to deliver additional pressure, that is to say, will cause the engine to be supercharged, the Venturi tube

50 and associated parts accomplish this object in the following manner: In Fig. 2, the parts are positioned as they would be at sea level and are positioned to cause the engine to be supercharged. With the valve 26

55 open, air from the pipe 21 escapes to the atmosphere through the mouth 23, which, due to the well-known action of the venturi, will cause a lowering of the pressure within the annular collar 24 and consequently a lower-

60 ing of the pressure within the space S, which is already described, will cause the engine to be supercharged.

As the airplane rises, the air confined within the casing 33 expands, due to a low-

ering of the pressure within the casing 30, 65 this casing, being as described, in connection with the atmosphere through the opening 31. This will cause the rise of the liquid level within the casing 30 and a raising of the float 28 and closure of the valve 26. 70 When the valve 26 is closed, the space S, through the pipes 20 and 21, is in ordinary direct connection with the delivery of the air compressor. In other words, as the airplane rises, the supercharging action is automatically dispensed with. 75

By manipulation of the bellows 35 by handle 36, it is evident that the device may be caused to initiate a supercharging action at any desired point. If, however, the 80 manual means are not used, the device of itself automatically cuts out the supercharging action as the airplane rises.

The ability to supercharge the engine is evidently useful in case an excess of power 85 is desired to rise from rough ground or rough water or to escape from or catch a hostile flying machine. Again, the propeller may be designed for operation at higher altitudes and so be adapted for higher 90 speeds. This higher speed may be attained even at sea level by the described supercharging means.

While I have described an embodiment of my invention, it should be understood that it 95 may be carried out in other ways and that the claims be construed accordingly.

I claim:

1. In combination, an air compressor, means responsive to the delivery pressure 100 of said compressor to control the delivery pressure of said compressor and means responsive to the atmospheric pressure to influence said first-mentioned means to cause said compressor to deliver additional pressure. 105

2. In combination, an air compressor, means to cause said compressor to normally deliver air at a substantially constant pressure and means responsive to the 110 atmospheric pressure to influence said controlling means to cause the compressor to deliver air at a pressure in excess of said normal delivery pressure.

3. In combination, an air compressor, 115 means to control the delivery pressure thereof so that a normal substantially constant pressure is maintained and means responsive to the atmospheric pressure to influence said controlling means to cause 120 said compressor to deliver additional pressure at lower altitudes and the normal pressure at higher altitudes.

4. In combination, an air compressor, means to control the delivery pressure of 125 the compressor, means connecting said controlling means to said air compressor and means, responsive to the atmospheric

pressure, to reduce the pressure in said connecting means below the delivery pressure of the compressor.

5. In combination, an air compressor, 5 means responsive to the compressor pressure to control the delivery pressure of the compressor, a pipe connecting said controlling means to said compressor, a Venturi tube associated with said pipe and 10 means responsive to the atmospheric pressure controlling the action of said Venturi tube.

6. The combination as claimed in claim 1, said second mentioned means being also 15 manually operable.

7. The combination as claimed in claim 2, said second mentioned means being also manually operable.

8. The combination as claimed in claim 3, said second mentioned means being also 20 manually operable.

9. The combination as claimed in claim 4, said third mentioned means being also manually operable.

10. The combination as claimed in claim 5, said atmospheric responsive means being also 25 manually operable.

In testimony whereof I affix my signature.

EARL H. SHERBONDY.
